ILLUMINABLE SUCTION-BLOWER INSECT TRAP OR SIMILAR ARTICLE

Read Viemeister, Yellow Spring, Ohio, assignor to
Ampco Corporation, Columbus, Ohio, a corporation of
Ohio

Filed Mar. 20, 1961, Ser. No. 64,385

Term of patent 14 years

(Cl. D31—3)

FIG. 1 is a front perspective view of an illuminable suction-blower insect trap or similar article showing my new design;

FIG. 2 is a side elevational view thereof;

FIG. 3 is a rear elevational view thereof with the insect receptacle omitted for convenience of illustration and a portion of the electric cord broken away to show indeterminate length;

FIG. 4 is a top plan view thereof as shown in FIG. 3 but with the end of the electric cord broken off for convenience of illustration;

FIG. 5 is a bottom plan view thereof as shown in FIG. 4.

The dominant features of my design reside in the full line portions of the drawing.

I claim:

The ornamental design for an illuminable suction-blower insect trap or similar article, substantially as shown and described.
